DRY SHAVING DEVICE

Ernest Charles McClure, Wahroonga, New South Wales, Australia, assignor to Ever-Ready Razor Products Ltd., The Hyde, London, England

Application April 7, 1939, Serial No. 266,447
In Great Britain January 5, 1939

17 Claims. (Cl. 30—43)

In one of its aspects, this invention relates to that type of appliance generally referred to as a dry shaver in which relative movement of the cutting edges is effected without the use of a motor and by and as the appliance is moved over the surface of the face. In another of its aspects this invention relates to a novel arrangement for maintaining contact between the relatively movable cutting edges of a dry shaving instrument.

In its first mentioned aspect, my invention contemplates an instrument in which the face engaging member takes the form of a cylindrical element mounted for free rotation and therefore free to rotate by traction as the instrument is moved across the face and having areas removed as by perforations to provide it with one or more cutting edges, and a second member which is held against rotation and is provided with one or more cutting edges engaging with the inner surface of the cylindrical element whereby as the instrument is moved across the face, the cylindrical element will rotate freely by traction and a hair entered through a perforation in the cylindrical element will be cut upon relative movement of the cylindrical element and the cutting edges effected by and as the instrument is moved across the face.

In this type of instrument it is desirable that the outer cylindrical member be made relatively thin, in fact as thin as practicable, reflecting manufacturing requirements, effectiveness in use and durability. It is necessary that close contact be had between the cutting edge (or edges) of the inner cutting member and that portion of the inner surface of the cylinder in engagement with the face, as otherwise there will be a tendency for the hairs to be pulled. In the illustrated embodiment I show a preferred arrangement whereby a contact is attained and maintained which is slight. This arrangement comprises supporting the blade so that it is free to swing about an axis located to the rear of the line along which the cutting edge engages with the inner surface of the cylinder and as an ancillary feature a member yieldably engaging the blade so as to position its edge in proximity to the inner surface of the cylindrical element so that only a slight rubbing contact with the inside of the cylinder is effected during the cutting operation.

It is the general object of my invention to provide a simple, inexpensive and effective dry shaving instrument which requires no experience or skill to operate.

In order to enable the invention to be fully understood one construction according thereto will now be described with reference to the accompanying drawings, in which:

5 Figure 1 illustrates the dry shaving device according to the invention pictorially.

Figure 2 is a longitudinal cross section of the device, the scale being about four times full size,

10 Figure 3 is a cross section on the line III—III of Figure 2, the scale in this case being eight times full size, but showing a modification including a second set of blades;

15 Figure 4 is a perspective view of the perforated cylinder,

Figure 5 is a perspective view of the blade carrier and blades, and

Figure 6 shows one of the blades.

20 In the construction illustrated in the drawings the device comprises an exterior hollow cylinder 1 made of a high grade steel of the kind employed in the manufacture of edge tools. The walls of this cylinder are very thin, that is to say, as thin as permitted by strength and manufacturing considerations, for example from .002" to .004", .003" being a convenient thickness in practice. The walls of the cylinder are perforated with small holes 2 dimensioned and spaced preferably as follows: the diameter of these holes is about .02" and the holes are spaced apart .05" around the cylinder and the adjacent rows of holes running round the cylinder are staggered. The spacing of the holes along the length of the cylinder is also .05".

35 One end of the cylinder is shown as permanently closed by a dished cap 3, and the other end as provided with a removable cap 4. Located within the cylinder is a blade carrier comprising two end bosses 5, 5a, connected by a shaft 6 to which they are secured as by set screws 5b. Each of the bosses has a flange 1, 1a, and these flanges are of the same diameter as the internal diameter of the cylinder 1, so that the blade carrier can be pushed into the cylinder, after which the removable cap 4 is pushed on to the end of the cylinder, the assembly being held in place by screws 8 passing through fork arms 9 of a handle 10 and entering screw threaded holes in extensions 11 of the blade carrier.

40 In order to maintain the blade carrier in a predetermined relation to the handle one arm 9 of the latter is provided with a projection 12 engaging a recess 13 in one of the extensions 11 of the blade carrier.

55 By means of the construction just described

the cylinder 1 is free to rotate relatively to the blade carrier 5, 6 and the handle 10.

In the construction illustrated in the drawings the blade carrier carries six blades 14, although this number may vary, these blades being mounted in the blade carrier with the relationship to the handle 10 as shown in Figure 3. Each blade is of the form shown in Figure 6 and comprises a portion having a cutting edge 14a and two trunnions 15 one at each end, these trunnions engaging in holes 16 formed in the flanges 7 of the blade carrier (see Figure 2). It will be observed from the drawings that each blade has its trunnions 15 received in the holes 16, along a line which is inwardly of the surface of the cylinder and to the rear of the line of contact therewith of the blade edge, with reference to the relative direction of motion of said edge during its hair cutting performance.

In order to insert the blades the set screws 5b are loosened and the bosses 5, 5a are moved apart along the shaft 6. The blades are then inserted and the bosses 5, 5a moved towards one another until they are at the required spacing to retain the blades.

In order to maintain the blades in contact with the internal surface of the cylinder 1, each blade is provided with a pair of leaf springs 17 fixed in corresponding radial slots in the portions 5, 5a of the carrier as shown in Figures 2 and 3.

The cutting edges 14a of the blades are disposed so as to make slight rubbing contact with the inside of the cylinder 1 so that as the cylinder is rotated by being passed over the face the hairs entering the perforations 2 therein are sheared off by the action of the perforations passing across the cutting edge of one or other of the blades 14.

As shown in the drawings each end of the cylinder is provided with a band 18 of rubber or like friction material which increases the grip of the cylinder on the face. It may be pointed out that when such bands are employed the peripheral speed of the portion of the cylinder which is of smaller diameter, that is to say, the portion between the two bands will be less than the peripheral speed of the bands themselves which are in contact with the face. Nevertheless the pressure of the device on the face will cause the central perforated portion of the cylinder to be in contact with the face, and since the peripheral speed of the central portion of reduced diameter is less than that of the two bands which by contact with the face are causing rotation of the cylinder, the central portion will slip over the face to an extent proportional to the difference in diameters and this slipping action will effect a combing of the hairs and facilitate their entry into the perforations.

From the foregoing it will be seen that in constructions of dry shaving devices according to the invention no motive power is required other than the friction of the cylinder 1 on the face of the user which is sufficient to cause the cylinder to rotate relatively to the blades 14.

The handle 10 is so positioned relatively to the blades that when holding the handle in a position convenient to the user, for example a vertical position, the blades are adjacent to the face of the user, although of course they are prevented from coming into direct contact therewith by the perforated cylinder which encloses them.

In the construction shown in the drawings the blades 14 are arranged with respect to the handle 75

10 so that the device will cut when moved over the face in the direction of the arrow A in Figure 3. By reversing the inclination of the blades the device may be made to cut when moved in a direction opposite from that of the arrow A. Further by providing a second set of blades 14' on the opposite side of the centre line from the blades 14 the device may be used to cut when moved in either direction.

10 In a modified form of the invention the closure discs for the ends of the perforated cylinder may be formed with cam surfaces on their inside faces, these cam surfaces engaging with pins projecting from the bosses 5 and 5a of the blade carrier so as to cause a slight longitudinal reciprocation of the blade carrier as the cylinder rotates. In such constructions the shaft 6 would be mounted for reciprocation while being prevented from rotation.

I claim:

1. A dry shaver comprising a frame, a hollow cylindrical face engaging member mounted on said frame for free rotation about the axis of the cylinder whereby it will be rotated by traction as the frame is moved across the face said cylindrical member having an opening therein providing a cutting edge, a second member provided with a cutting edge, means for pivotally supporting said second member from the frame so that its cutting edge is free to swing into contact with the inner surface of the cylindrical member, and means for maintaining the edge swung about its pivot to a position of close adjacency to the inner surface of the cylindrical member, the cylindrical member being free to rotate relatively to said second member and its cutting edge and said second member being held to the frame, whereby a relative movement will be effected between the aforementioned cutting edges by traction as the frame is moved across and in engagement with the face.

2. In a dry shaver, a frame a hollow cylindrical face engaging member mounted for free rotation on said frame so as to be rotatable by traction as the frame is moved across the face, said member having openings therein so as to provide cutting edges, a second member provided with a cutting edge adapted to engage with the inner surface of said cylindrical member, means on the frame for pivotally supporting said second member for swinging about an axis to the rear of the line of contact of said cutting edge with the inner surface of said cylindrical member, whereby as the instrument is moved across the face, a hair entered into the opening in said cylindrical member will be cut upon relative movement of the cylindrical member to said second member effected by movement of the instrument across the face.

3. In a dry shaver, a frame, a hollow cylindrical face engaging member mounted for free rotation on said frame so as to be rotatable by traction as the frame is moved across the face, said member having openings therein so as to provide cutting edges, a second member provided with a cutting edge engaging with the inner surface of said cylindrical member, a pivotal mounting on said frame for said second member whereby it is pivotable about an axis to the rear of the line of contact of said cutting edge with the inner surface of said cylindrical member, whereby as the instrument is moved across the face a hair entering the opening in said cylindrical member will be cut upon relative movement of the cylindrical

member to said second member effected by movement of the instrument across the face.

4. In a shaving appliance, an inner member, a cutter in the form of a hollow thin-walled drum adapted to be rolled over a surface to be shaved and mounted for free rotation relatively to said inner member, and said drum being perforated providing cutting edges on the inner surface thereof, a cutting blade mounted for pivotal movement on said inner member, and resilient means having a portion resting on said inner member and adapted to maintain said cutting blade in cutting relation with the cutting edges on the inner wall of said drum.

5. A shaving appliance comprising an inner member, a cutter, in the form of a hollow thin-walled drum adapted to be rolled over a surface to be shaved and mounted for free rotation relatively to said inner member, and the walls of said drum being perforated, a cutting blade provided with a cutting edge, said blade being mounted for limited free pivotal and lateral movement on said inner member, resilient means for maintaining the cutting edge of said blade in contact with the inner wall of said drum, with the blade disposed at an acute angle to said inner wall, and a second cutting blade similar to said first cutting blade and mounted similarly thereto, but directed oppositely thereto.

6. A dry shaving device comprising in combination a frame, a hollow cylinder freely rotatable in said frame, the walls of said cylinder being very thin and provided with small perforations, and a cutting element provided with a cutting edge non-revolably pivoted to said frame and disposed within said cylinder, said cutting element having its cutting edge slidably engageable with the internal surface of said cylinder, whereby by moving the cylinder over the face of the user said cylinder is caused to revolve relatively to said cutting element while said cutting element moves with the frame without revolving.

7. A dry shaver comprising a frame, a hollow cylindrical face engaging member mounted on said frame for free rotation about the axis of the cylinder whereby it will be rotated by traction as the frame is moved across the face said cylindrical member having an opening therein providing a cutting edge, a second member provided with a cutting edge, means for pivotally supporting said second member from the frame and means to cause its cutting edge to contact with the inner surface of the cylindrical member, the cylindrical member being free to rotate relatively to said second member and its cutting edge and said second member being held to the frame, whereby a relative movement will be effected between the aforementioned cutting edges by traction as the frame is moved across and in engagement with the face.

8. A dry shaver device comprising in combination a frame, a hollow cylinder freely rotatable on said frame, the walls of said cylinder being thin and provided with small perforations, a plurality of cutting blades pivotally carried by said frame, spring means cooperating with each blade to hold its cutting edge in contact with the inner surface of said cylinder, the cutting edges of the blades being spaced apart over a portion of said inner surface whereby upon rotation of the cylinder by traction as it is moved over the face relatively to the cutting edges the cutting edges will shear hairs admitted through the perforations in the cylinder.

9. A dry shaver device comprising in combina-

tion a frame, a hollow cylinder freely rotatable on said frame, the walls of said cylinder being thin and provided with small perforations, a plurality of cutting blades pivotally carried by said frame, spring means cooperating with each blade to hold its cutting edge in contact with the inner surface of said cylinder, one group of said blades being angled in one direction to present their edges in spaced apart relation over a portion of said inner surface and another group being angled in an opposite direction to present their edges over another portion of said inner surface whereby upon rotation of the cylinder by traction as it is moved over the face in one direction the edges of one group of blades will become active to shear hairs admitted through the perforations in the cylinder and upon rotation of the cylinder in the opposite direction the edges of the other group of blades will become active to shear said hairs.

10. In a dry shaver the combination with a frame and a hollow cylindrical face engaging member mounted for free rotation on said frame so as to be rotatable by traction as the frame is moved across the face and having hair admitting openings therein, of a cutter assembly comprising opposed flanges carried by the frame and positioned within the cylindrical member with the flanges in spaced relation longitudinally of the cylinder, and a blade pivotally mounted at its ends in said opposed flanges at a distance from said cylindrical member less than the width of the blade so that the blade edge may swing into cutting relation to the inner surface of the cylindrical member.

11. In a dry shaver the combination with a frame and a hollow cylindrical face engaging member mounted for free rotation on said frame so as to be rotatable by traction as the frame is moved across the face and having hair admitting openings therein, of a cutter assembly comprising opposed flanges carried by the frame and positioned within the cylindrical member with the flanges in spaced relation longitudinally of the cylinder, and a blade pivotally mounted at its ends in said opposed flanges at a distance from said cylindrical member less than the width of the blade so that the blade edge may swing into cutting relation to the inner surface of the cylindrical member, said assembly being removable from and replaceable into the cylindrical member as a unit.

12. In a dry shaver the combination with a frame and a hollow cylindrical face engaging member mounted for free rotation on said frame so as to be rotatable by traction as the frame is moved across the face and having hair admitting openings therein, of a cutter assembly comprising opposed flanges carried by the frame and positioned within the cylindrical member with the flanges in spaced relation longitudinally of the cylinder, and a plurality of blades each pivotally mounted at its ends in said opposed flanges at a distance from said cylindrical member less than the width of the blade so that its edge may swing into cutting relation to the inner surface of the cylindrical member, said pivots being circumferentially spaced with relation to the inner surface of the cylindrical member so that the blade edges shall engage said inner surface of the cylindrical member at spaced points.

13. In a dry shaver the combination with a frame and a hollow cylindrical face engaging member mounted for free rotation on said frame so as to be rotatable by traction as the frame is moved across the face and having hair admitting

openings therein, of a cutter assembly comprising opposed flanges carried by the frame and positioned within the cylindrical member with the flanges in spaced relation longitudinally of the cylinder, and a plurality of blades each pivotally mounted at its ends in said opposed flanges at a distance from said cylindrical member less than the width of the blade so that its edge may swing into cutting relation to the inner surface of the cylindrical member, said pivots being circumferentially spaced with relation to the inner surfaces of the cylindrical member so that the blade edges shall engage said inner surface of the cylindrical member at spaced points, one group of said blades having the edges thereof presented to said cylindrical surface in one direction, and the other group of said blades having the edges thereof presented in the other direction, whereby one group will shear upon movement of the cylindrical member in one direction and the other group will shear upon movement of the cylindrical member in the other direction.

14. In a dry shaver, the combination with a frame and a hollow cylindrical face engaging member mounted for free rotation on said frame so as to be rotatable by traction as the frame is moved across the face and having hair admitting openings therein, of a cutter assembly comprising a member received within the cylindrical member and held against rotation relatively to the frame, opposed spaced flanges extending outwardly from said member, a blade pivoted at its ends in said flanges at a distance from said cylindrical member less than the width of the blade so that its edge can be freely swung into cutting relation to the inner surface of the cylindrical member, and means carried by the member and engaging the blade to maintain the edge of the blade yielding in such cutting relation.

15. In a dry shaver, the combination with a frame and a hollow cylindrical face engaging member mounted for free rotation on said frame so as to be rotatable by traction as the frame is moved across the face and having hair admitting openings therein, of a cutter assembly comprising a member received within the cylindrical member and held against rotation relatively to the frame, opposed spaced flanges extending outwardly from said member, a blade pivoted at its ends in said flanges at a distance from said cylindrical member less than the width of the blade so that its edge can be freely swung into cutting relation to the inner surface of the cylindrical member, and means carried by the member and engaging the blade to maintain the edge of the blade yielding in such cutting relation, said as-

sembly being removable from and replaceable in-
to said cylindrical member as a unit.

16. In a dry shaver, the combination with a frame and a hollow cylindrical face engaging member mounted for free rotation on said frame so as to be rotatable by traction as the frame is moved across the face and having hair admitting openings therein, of a cutter assembly comprising a member received within the cylindrical member 5 and held against rotation relatively to the frame, opposed spaced flanges extending outwardly from said member, a plurality of blades each pivoted at its ends in said flanges at a distance from said cylindrical member less than the width of the 10 blade so that its edge can be freely swung into cutting relation to the inner surface of the cylindrical member, and means carried by the member and engaging the blade to maintain the edge of the blade yielding in such cutting relation, said 15 pivots being circumferentially spaced with relation to the inner surface of the cylindrical member so that the blade edges shall engage said inner surface of the cylindrical member at spaced points.

20

25 17. In a dry shaver, the combination with a frame and a hollow cylindrical face engaging member mounted for free rotation on said frame so as to be rotatable by traction as the frame is moved across the face and having hair admitting openings therein, of a cutter assembly comprising a member received within the cylindrical member and held against rotation relatively to the frame, opposed spaced flanges extending outwardly from said member, a plurality of blades 30 each pivoted at its ends in said flanges at a distance from said cylindrical member less than the width of the blade so that its edge can be freely swung into cutting relation to the inner surface of the cylindrical member, and means carried by 35 the member and engaging the blade to maintain the edge of the blade yielding in such cutting relation, said pivots being circumferentially spaced with relation to the inner surface of the cylindrical member so that the blade edges shall engage said inner surface of the cylindrical member 40 at spaced points, one group of said blades having the edges thereof presented to said cylindrical surface in one direction, and another group of said blades having the edges thereof presented in 45 the other direction, whereby one group will shear upon movement of the cylindrical member in one direction and the other group will shear upon movement of the cylindrical member in the other direction.

ERNEST CHARLES MCGLYNN
